Primary Examiner — Darcey E Gottschalk(74) *Attorney, Agent, or Firm* — Kevin C. Johnson; Andrés E. Velarde(57) **CLAIM**

The ornamental design for a razor package, as shown and described.

DESCRIPTION

FIG. 1 is a front perspective view of a design of a razor package of the present invention; and, FIG. 2 is a front view thereof.

In the drawings, the broken lines show portions of a razor package that form no part of the claimed design.

1 Claim, 2 Drawing Sheets(56)
